(57) **CLAIM**

The ornamental design for a multi-function printer, as shown and described.

DESCRIPTION

FIG. 1 is a left front top perspective view of a multi-function printer, showing my new design;

FIG. 2 is a right front top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is another left front top perspective view thereof; and, FIG. 10 is an enlarged view of an encircled portion in FIG. 9.

The broken lines shown in the figures are for the purpose of illustrating portions of the multi-function printer and form no part of the claimed design.
